OXIDATION OF SIDE CHAIN AROMATIC COMPOUNDS

Alphons O. Jaeger, Mount Lebanon, Pa., assignor to The Selden Company, Pittsburgh, Pa., a corporation of Delaware

No Drawing. Application December 11, 1929
Serial No. 413,426

7 Claims. (Cl. 260—108)

This invention relates to catalytic vapor phase oxidation of side chain aromatic compounds.

The catalytic oxidation of side chains of aromatic compounds to produce aldehydes and acids is a very delicate reaction, and it has not been possible in the past to produce satisfactory yields with good outputs even when using highly efficient catalysts. The control of the reaction appears to be so delicate that if a sufficient contact time is provided to assure a satisfactory percentage of conversion a large amount of the product is further oxidized.

The present invention is based upon the surprising discovery that if the reaction is split up into a number of parts the conditions can be satisfactorily controlled. The present invention is carried out by passing vapors of a side chain compound admixed with an oxygen-containing gas through a series of converters, the product being condensed out between converters and the exhaust gases containing the unreacted portion of the side chain compound being passed through the following converter. Remarkable increases in yield are obtained, and under the most favorable circumstances it is possible to obtain conversion efficiencies of typical side chain compounds to acids, for example toluene to benzoic acid, of more than 70%, which compares with production efficiencies at commercial practical loadings of 30% or less when a single converter is used.

The invention is in no sense limited to the use of any particular number of converters, the number used depending largely on the economics of the process; thus, for example, with an expensive raw material a larger number of converters can be profitably employed than with a cheaper raw material where the capital investment for converters and the labor cost is a relatively large item. A marked increase in efficiency is noted when as few as two converters are used in series, but I have found that it is desirable to use at least four converters in series. The production of the first three converters is about the same, the fourth converter beginning to show considerable falling off, and, of course, with a larger number of converters each additional converter gives a proportionately smaller increase in yield. The number of converters which should be used is also to some extent dependent on the particular compound used, the more delicate the reaction the larger the number of converters which will ordinarily be economically desirable.

While the present invention presents an important improvement over the prior processes

when fresh reaction gases are used in the first converter, it is desirable in order to get maximum yield to recirculate a part of the reacted gases. This may take place by pumping a portion of the exhaust gases from the last converter in the series into the reaction gas stream entering the first converter, or, if desired, the recirculation can be for each converter in the series. Recirculation has a marked effect on the yield. Under ordinary conditions, for example, with a given catalyst and four converters a conversion of toluene of somewhat more than 50% is obtained without recirculation. With recirculation of three-fifths of the exhaust gases from the last converter the production yield rises to better than 70%. It should be noted, however, that if the catalyst is loaded to such a point that the production of benzoic acid is as high as the catalyst can give, recirculation does not seem to raise the yield any. This would indicate that the recirculation primarily prevents destruction of the product already formed, but does not aid in accelerating the oxidation of the side chain compound itself. It should be understood, however, that this is not definitely proven, and it is possible that other factors may be involved, and, accordingly, the invention is in no sense limited to any theory of action of the recirculation and, of course, is not limited to recirculation, which constitutes merely the preferred embodiment.

The present invention is applicable generally to the oxidation of all side chain aromatic compounds such as toluene and its substitution products, as halogenated toluenes, nitrotoluenes, etc. to the corresponding benzoic acids and benzaldehydes; homologues of toluene, such as xylenes, mesitylene, and the like. The production in the case of toluenes is mainly benzoic acid when a benzoic acid catalyst is used, but benzaldehyde may also be produced as the main product when a suitable benzaldehyde catalyst is employed. The benefits of the invention are applicable to both reactions.

The present invention is not limited to any particular type of converters, but it is advantageous to maintain uniform temperatures and, therefore, converters having relatively small catalyst compartments, such as, for example, tubular converters whose temperatures are controlled by baths, either boiling or non-boiling, can be very effectively employed, although the invention is in no sense limited to their use and other types of converters, such as reaction gas-cooled converters, and the like, may be used.

Iron converters tend to form layers of iron oxide, which appears to act as a combustion catalyst and increases losses due to destruction of the oxidation product. It is, therefore, desirable to inactivate the converter walls coming in contact with the reaction gases, either by using special steels or other metals which do not form oxides of iron under the reaction conditions or by coating the walls with a compound of an alkali, alkaline earth, or earth metal which forms a layer which is not a combustion catalyst. Of course, the invention is not limited to converters thus inactivated, this being merely an advantageous feature in the preferred modification.

The temperature at which the reaction takes place may be varied within considerable limits, good results being obtained in the case of bath cooled converters at bath temperatures between 350 and 450° C., and the optimum temperature for the production of benzoic acid of the highest quality from toluene being about 380° to 390° C. for a bath cooled converter. It should be understood that the temperatures will vary somewhat with the nature of the catalyst and that the invention is in no sense limited to the temperature ranges given above, which constitute merely preferred ranges. When aldehydes are to be produced, of course, lower temperatures are in general used than when acids are to be produced, the temperatures varying, however, with the particular catalyst.

The amount of fresh air used may be varied within wide limits, for example from 3½ to 20 liters per gram of side chain compound oxidized. In general the amount of fresh air will be least where the proportion of recirculated air is greatest, but this depends to a considerable extent on the loading and on the nature of the catalysts. The invention is in no sense limited to the ranges given.

In most installations fresh vapors of the side chain aromatic compound enter only the first converter of the series. This type of installation presents advantages from the equipment standpoint, but the invention is not limited to such constructions and it is sometimes advantageous to introduce fresh side chain aromatic compound into one or more converters of the series after the first. Systems with such auxiliary introduction are included within the scope of the present invention, and for some of the reactions covered by the invention they present important advantages in higher yield and smoothness of control.

The invention will be illustrated in greater detail in connection with the following specific examples, which are illustrative embodiments only.

Example 1

Four converters are arranged in series with small tubes and catalyst heights of from 30-50 cm., the volume of catalyst in each tube being about 150 c.c. The converters are filled with catalyst consisting in a diluted potassium vanadyl vanadate prepared according to Example 15 of United States Patent No. 1,709,853 to A. O. Jaeger. The tubes of each converter are surrounded by a suitable bath maintained at 380° C. for the first converter and 390° C. for the last three converters. The toluene vapors, admixed with air, are passed through the converter in series without recirculation, the amount of air being 140 liters per hour per tube and the amount of toluene being 12 grams per hour per tube. Most of the conversion takes place in the first three converters, the product being condensed out between

each pair, and a total yield of around 50% is obtained, most of which is benzoic acid.

Example 2

Converters are set up as described in Example 1, but instead of introducing fresh reaction gases only into the first converter, a mixture of 40 liters of fresh air per hour and 160 liters of exhaust gases are used, about 8 grams of toluene per hour per tube being vaporized. The production is over 70%, the majority of which is benzoic acid. It should be noted that with this lower loading the 4th converter gives 10% conversion.

Example 3

Converters are set up as in Example 2, but are filled with a benzaldehyde catalyst in the form of a diluted zeolite containing tantalum, molybdenum, tungsten and uranium in non-exchangeable form and prepared according to Example 13 of United States Patent No. 1,709,853 to A. O. Jaeger. The bath is maintained at 450° instead of 380 to 390° C., and toluene is vaporized and passed through with fresh air and exhaust gases as described in Example 2. A high yield of product is obtained, the major portion of which is benzaldehyde, the unreacted toluene, of course, being recirculated in part and in part recovered from the exhaust gases which are vented, for example by absorption in activated carbon or silica gel.

Example 4

A converter system is arranged as described in Example 2, but chlorotoluene is passed over instead of toluene. The output is better than 80% of a product which is mainly chlorbenzoic acid.

Example 5

A converter system is set up as described in Example 2, but xylene or chlorxylyne is used instead of toluene or chlorotoluene. The conversion to the corresponding acids and aldehydes is a few percent less than with the corresponding toluenes.

What is claimed as new is:

1. A method of producing an acid from a side chain aromatic compound, which comprises vaporizing the compound, admixing it with an oxygen-containing gas in amounts considerably in excess of that theoretically required for the side chain oxidation and passing the mixture in series through a plurality of converters filled with a catalyst favoring the oxidation of side chain aromatic compounds to acids at a temperature of approximately 380-390° C., the converted product being condensed out between each pair of converters.

2. A method according to claim 1, in which at least part of the exhaust gases from the last converter is recirculated into the intake of at least one converter earlier in the series.

3. A method according to claim 1, in which at least part of the exhaust gases of the last converter is recirculated into the intake of the first converter.

4. A method of producing a benzoic acid from toluene, which comprises vaporizing the toluene, admixing it with an oxygen-containing gas in amounts considerably in excess of that theoretically required for the side chain oxidation and passing the mixture in series through a plurality of converters filled with a catalyst favoring the oxidation of the toluene to benzoic acid at a temperature of approximately 380-390° C., the converted product being condensed out between each pair of converters.

verted product being condensed out between each pair of converters.

5. A method according to claim 4, in which at least part of the exhaust gases from the last converter is recirculated into the intake of at least one converter earlier in the series.

6. A method according to claim 4, in which at least part of the exhaust gases of the last con-

verter is recirculated into the intake of the first converter.

7. A method according to claim 4, in which fresh vapors of the side chain compound are introduced directly into at least one converter of the series other than the first converter.
